UNITED STATES PATENT OFFICE.

JIM A. GRANT, OF CHICAGO, ILLINOIS, AND GEORGE A. LOWRY, OF NEW YORK, N. Y.

BRICK-CLEANING MACHINE.

Application filed July 5, 1924. Serial No. 724,200.

This invention relates to improvements in brick cleaning machines and has for its object the production of a construction which will quickly, economically and efficiently remove mortar, cement or other adhering material from the surfaces of bricks that have been used in construction work.

Another object of our invention includes the production of a brick cleaning machine which is provided with means for giving the material adhering to the brick to be cleaned a live hammer blow.

A further object embraces the provision of means for securely holding the bricks to be cleaned and which operate in conjunction with mechanism for advancing said brick in synchronism with the movement of the cleaning mechanism.

Other objects will appear hereinafter, and we attain these results by the mechanism illustrated in the accompanying drawings, in which:—

Fig. 1 is a view in elevation of a construction which embraces the principles of our invention.

Fig. 2 is a plan view thereof.

Fig. 3 is an end view thereof showing the striker in raised position.

Fig. 4 is a view similar to Fig. 3 but showing a different type of brick clamp.

Fig. 5 is a plan view of the portion shown in Fig. 4.

Fig. 6 is a view of the brick clamp of Fig. 4, wherein the clamp operating finger is shown.

Fig. 7 is a view in elevation of one form of clamp.

Fig. 8 is a plan view thereof showing its attachment to the carrier chains.

Fig. 9 is a view of a different form of striker mechanism.

Like numerals refer to similar parts throughout the several views.

It is our prime object to provide a labor saving machine, which at the same time cleans bricks more quickly and efficiently, than can be done by the tedious and laborious hand method, or by any cleaning machine known to us. To this end, we employ mechanism whereby the material to be removed from the bricks is given a sharp hammer blow by suitable mechanism, shearing down simultaneously on both of the flat faces of the brick undergoing the cleaning process.

The cleaning blow is heavy enough to remove all adhering material from the bricks

and it is delivered quickly so that the progressive movement of the brick is uninterrupted. Unclean bricks are constantly fed into the machine at one side and these advance into the cleaning position, where the cleaning mechanism imparts its hammer blow to the material to be removed, at intervals of about a second to as many bricks, thus cleaning approximately fifty to sixty bricks in a minute. This speed, however, is varied as occasion requires. The cleaned bricks are automatically released from the automatic gripping clamp in which they are held while undergoing the cleaning process.

As examples of specific embodiments in constructions which involve the principles of our invention, we have shown, in the accompanying drawings, mechanism for carrying out our objects of the invention. Said mechanism comprises, in a preferred form, a suitable bed or frame 10 supported on standards 11. On to this bed are bolted, or otherwise fastened, cross arms 12 for supporting the brick conveyor frame 13 which carries the brick conveyor 14 and the uprights 15, 15 and 16, 16 for supporting the cleaning and operating mechanism.

The operating mechanism comprises a suitable drive shaft 17 supported in the standards 15, 15. This shaft carries a power element or pulley 18 at one end and a beveled pinion 19 at the other. The beveled pinion 19 meshes with a similar pinion 20 on shaft 21 for driving the brick conveyor 14 by means of a chain 22 or its equivalent, operating on suitable sprockets 23 and 24. A suitable adjustment screw 25 permits adjusting the conveyor to synchronize with the cleaner mechanism, as will directly appear more fully.

The conveyor comprises, in a preferred form, a pair of continuous link chains 14'-14' having ear links 26 for fastening the brick carrying clamps 27 or 28 thereto at proper intervals. The brick clamps comprise means for receiving and holding the bricks while they are conveyed beneath the cleaning device or chopping mechanism 29 for being cleaned. Suitable forms of clamps are indicated by the numeral 27 in Figs. 4 or 5 and by 28 in Figs. 1, 2, and 8. Any suitable clamp with the necessary operative devices will suffice to hold the brick. In the form represented by the numeral 27 the base 31 is fastened on to

the conveyor chains 14'-14' by the ears of links 26 and this base carries a bracket arm 32 and spring 33. Arm 32 is provided with jaws 34 for receiving the lever arm 35, 5 the latter being pivotally held on a pivot bolt 36. At one extremity of the lever arm 35 the clamping plate 37 is pivotally mounted by bolt 38. The other end of said arm is provided with a bearing roller 39 10 for engaging cam 40 to open the clamp at opportune times to receive or discharge the brick. The compression spring 33 is held in place by any suitable means, as heads 41 and 42, having holding pins 43 and 44. 15 The clamping plate 37 is preferably weighted as at 45 to overbalance the plate when the clamping jaw is opened by reason of the roller 39 engaging cam 40 to depress this end of the lever and to raise the plate 20 holding end. The clamp is thereby opened to receive the brick 46. This action takes place at the end (A) of the conveyor, referring, for example, to Figs. 1 and 2. At this time a brick (46) is placed in position 25 so that the flat faces extend vertically and pass the striking planes of the cleaning mechanism, as the conveyor carries the clamp and its imprisoned brick forward. The clamp closes immediately after receiving 30 its brick by reason of the limited length of the cam 40, as is well understood in the art. Where clamps 28 are used, pins or teeth 47, 47' hold the bricks in the clamp while they are carried forward to undergo 35 cleaning as before. The active or clamping pins 47 are held in closed position by springs 48 and they are opened by the cams 49 or 49' bearing against the cam surface or roller 69, respectively to receive or to 40 discharge the bricks before and after cleaning. Either type of clamp is carried on the conveyor chains 14-14 or their equivalent, as described above. These chains operate over suitable sprockets 71 and 72 and are 45 driven by the drive chain 22 at a proper speed so as to bring a clamp with its brick in position so that the verticle faces of the brick pass through the striking planes of the cleaner with every revolution of the 50 drive shaft 17 and its operating cams 53, as will be more fully described hereinafter.

The brick cleaning device comprises a pair of parallel arms or shearing bars 51, or their equivalent, pivoted on a pivot bar 55 52 and rocked thereon by suitable cam construction 53 secured on the drive shaft 17 to rotate therewith. The shearing bars 51 are spaced apart, at the brick cleaning end, a distance somewhat greater than the thickness 60 of the brick and are so disposed as to simultaneously strike the adhearing material (50, 50) on both sides of the brick (46) as they descend. This action is effected by cut away portion of the rotary cam members 53 passing the ends 54 of the 65 bars 51 thereby causing the cleaner to be elevated and permitted to drop on to the moving brick as its faces pass the striking planes of the cleaner. Suitable weights 55 on the ends of bars 51 and a retracting 70 spring 56 serve to impart the proper hammer blow to the material which is to be removed. This action causes the material to be removed cleanly and quickly and usually in large pieces. 75

If desired striker or shearing plates 59 may be provided on the effective ends of the cleaner arms 51. These plates may be properly tempered to resist wear and they are attached for easy replacement when worn or dull. Obviously, the weights 55 or the tension of the retractor spring 56, or both, 80 may be varied to meet the condition of the material which is to be removed.

In place of the cam operated striker just 85 described, we may use the type illustrated in Fig. 9. Here the brick 46 is cleaned by the shearing plates 73, one of which is shown. These plates are carried by the cushioned plunger 74 which has a pin 175 90 engaging the elongated aperture 176 in stem 177. This stem is, therefore, cushioned by a spring 178 in plunger 74 when the assembly is operated on the supporting arm 75 by a walking beam 76, lever 77 and cam 78. This cam operates in the cam surface 79 and causes the plates 73 to oscillate in the so-called "striking planes" of the 95 cleaning mechanism described above.

From what has been disclosed, the operation of our brick cleaning machine is readily 100 understood and is substantially as follows:

The machine is driven from any suitable source of power through the agency of the pulley 18, which is operated at the desired 105 rate of speed. This motion is imparted to shaft 17 and the attached pinion 19 and cams 53. The rotary motion of cams 53 causes the cleaning mechanism and weight 110 to be raised against the tension of spring 56 thereby causing the weighted end of the cleaner to descend with force and to be then again elevated. The conveyor mechanism, with its spaced brick clamps, is caused to move in synchronism with the striker mechanism and the brick holding clamps are so spaced that they in turn are beneath the striker so as to present the sides of the brick to the striking bars. Bricks are placed in 115 the open clamps at A. The clamps then close and carry the bricks into cleaning position, and as the sides of the bricks reach the striking planes of the cleaner arms the cleaner descends and strikes off the mortar or cement from the sides of the brick, the 120 progress of which is not impeded thereby. As the cleaned brick reaches the discharge end of the conveyor, the holding clamp is 125 opened by a cam device similar to that at the feeding end A of the conveyor.

130

It is evident to those versed in the art that various modifications falling wholly within the spirit and scope of our invention may suggest themselves, and we do not therefore desire to limit ourselves unduly.

What we claim, therefore, as new and useful, of our own invention and desire to secure by Letters Patent, is:—

1. In a brick cleaning machine, the combination of means for temporarily gripping bricks to be freed from extraneous matter, means for imparting motion to said bricks while thus gripped, and means including spaced devices for imparting a striking blow to said extraneous matter to remove the same from said bricks.

2. In a brick cleaning machine, the combination of means for temporarily gripping bricks to be freed from extraneous matter, means for imparting constant motion to said bricks while thus gripped, and means including pivoted arms spaced to strike the extraneous matter for imparting a hammer blow to said extraneous matter to remove the same from said bricks while the said bricks continue their forward travel.

3. In a brick cleaning machine, the combination of a brick cleaning device and means for operating said device intermittently, a conveyor and means for operating said cleaning device and conveyor in synchronism, a plurality of clamps on said conveyor, and means for temporarily rendering ineffective said clamps to receive and to discharge said bricks.

4. In a brick cleaning machine, the combination of a brick cleaning device and a conveyor, said cleaning device and conveyor acting in synchronism, of a plurality of brick clamps carried by said conveyor, means for opening said clamps to receive the bricks to be cleaned, means for holding closed said clamps, and means for intermittently rendering effective said brick cleaning device to disrupt foreign adhering matter from the brick.

5. In a brick cleaning machine, a base having a shelf extension, in combination with a brick cleaning device pivotally mounted on said base and a brick conveying mecha-

nism mounted on said shelf, means for moving said conveyor, means for intermittently oscillating said pivotally mounted brick cleaning device in synchronism with said conveyor, and means for intensifying the motion of said brick cleaning device to impart a hammer blow to the extraneous matter for removing the same from the brick.

6. In a brick cleaning machine, a base having a shelf extension, in combination with a brick cleaning device mounted on said base and a brick conveying mechanism mounted on said shelf, said device comprising a pair of cleaning jaws, means for moving said jaws upwards, and means for causing said jaws to strike a sharp blow to the extraneous matter on the sides of a brick to remove extraneous matter therefrom bodily.

7. In a brick cleaning machine, a base having a shelf extension, in combination with a brick cleaning device mounted on said base and a brick conveying mechanism mounted on said shelf, said device comprising a pair of cleaning jaws, means for moving said jaws upwards, means for causing said jaws to impart a disruptive blow to the extraneous matter on the sides of a brick to remove the same therefrom bodily, spring clamped jaws for engaging said bricks while cleaned, and cam surfaces for relaxing said jaws to receive or to discharge said bricks.

8. In a brick cleaning machine, a base having a shelf extension, in combination with a brick cleaning device pivotally mounted on said base and a brick conveying mechanism mounted on said shelf, means for moving said conveyor, means for intermittently oscillating said pivotally mounted brick cleaning device in synchronism with the motion of the brick on said conveyor, and a clamp for holding said brick while being cleaned, said clamp comprising a spring pressed arm, a cam engaging member on one end of said arm and a clamping plate on the other end of said arm.

In testimony whereof we have hereunto set our hands on this 3rd day of July A. D., 1924.

JIM A. GRANT.
GEORGE A. LOWRY.
